UNITED STATES PATENT OFFICE.

SAMUEL J. PEARSALL, OF SARATOGA SPRINGS, NEW YORK.

CAR-STARTER.

SPECIFICATION forming part of Letters Patent No. 415,924, dated November 26, 1889.

Application filed April 23, 1889. Serial No. 308,245. (No model.)

To all whom it may concern:

Be it known that I, SAMUEL J. PEARSALL, of Saratoga Springs, in the county of Saratoga and State of New York, have invented a new and Improved Car-STARTER, of which the following is a full, clear, and exact description.

The object of the invention is to provide a new and improved car-starter which is simple and durable in construction and very effective in operation.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is an inverted plan view of the improvement as applied. Fig. 2 is a longitudinal sectional elevation of the same. Fig. 3 is a detail view of the ratchet-wheel, and Fig. 4 is a plan view of the improvement.

The car A, to which the car-starter is applied, is provided with the usual axles B and B', on which are mounted the wheels C C and C' C', respectively, traveling on the car-track. On the rear axle B is held to rotate loosely a toothed wheel D, on one face of which are pivoted the pawls E E, pressed in contact by the springs F, with the teeth of a ratchet-wheel G secured on the axle B. The pawls E E are preferably located diametrically opposite each other, as plainly shown in Fig. 3.

On each side of the toothed wheel D is held to rotate loosely on the axle B a pulley II or II', over which pass the ropes or cords II, connected at their lower ends to a rope or cord I', extending forward and secured to one face of a clutch-wheel J, mounted to rotate loosely on the front axle B'. The clutch-wheel J is adapted to be engaged by a clutch-tooth C², formed on the inner face of one of the car-wheels C'. On the hub of the clutch-wheel J is formed an annular groove J', engaged by a loop K, forming part of a lever K', pivoted on the under side of the platform of the car A. The other end of the lever K' is pivotally connected with the lower end of a lever L, fulcrumed in the car-platform and extending vertically above the same, so as to be within con-

venient reach of the driver on the front platform of the car.

The upper ends of the ropes or cords I are connected with the end of a sprocket-chain N, connected with one end of a coil-spring O, extending longitudinally in a box P, formed on the upper side of the bottom of the car A, under one of the rows of seats in the car. The other end of the spring O is secured to a stud or screw Q, secured in the bottom of the box P, as is plainly shown in Fig. 2. On this stud or screw Q is also secured one end of a rope or rod R, passing through the center of the coil-spring O and connected with the end of the sprocket-chain N.

The operation is as follows: When the car-starter is inactive, as shown in Fig. 1, the clutch-wheel J is disengaged from the clutch-tooth C² and the coil-spring O is compressed, resting near the stud Q and holding the sprocket-chain N disengaged from the toothed wheel D. When the operator on the platform of the car desires to use the car-starter, he moves the lever L to one side, so that the lever K' swings and throws the clutch-wheel J into contact with the clutch-tooth C² on the car-wheel C'. The latter, on the forward motion of the car, rotates the clutch-wheel J, whereby the cords or ropes I are wound up on the hub of the said clutch-wheel and draw the sprocket-chain N into contact with the teeth of the toothed wheel D. As the latter rotates with the rear axle B by means of the ratchet-wheel G and the pawls E the sprocket-chain N is drawn over the toothed wheel D, thus extending the coil-spring O until the rope R is extended its full length, so as to prevent a further expansion of the coil-spring O. The car-starter has now accumulated force which is stored in the tension of the spring O. When the operator now desires to make use of the stored-up force, he moves the lever L in the opposite direction, so as to disengage the clutch-wheel J from the tooth C², whereby the spring O is free to act on the pulleys and the sprocket-chain N in the direction of the arrow a'—that is, in the same direction as the previous movement of the car. The sprocket-chain N, on account of being engaged by the teeth of the toothed wheel D, rotates the latter, and by its pawls

E imparts a rotary motion to the ratchet-wheel G, secured on the axle B, whereby the latter is rotated in the same direction—that is, impels the car forward in the direction of the arrow a'. The car thus receives a forward motion from the stored force of the coil-spring.

Having thus described my invention, what I claim as new, and desire to secure by Letters 10 Patent, is—

1. In a car-starter, the combination, with a toothed wheel held loosely on one of the car-axes, of spring-pawl's pivoted on said toothed wheel, a ratchet-wheel secured on the respective car-axe, on which the said toothed wheel rotates loosely, a sprocket-chain adapted to engage the said toothed wheel, and a spring connected at one end to the said sprocket-chain and at its other end to the car, substantially as shown and described.

2. In a car-starter, the combination, with a toothed wheel held loosely on one of the car-axes, of spring-pawl's pivoted on said toothed wheel, a ratchet-wheel secured on the respective car-axe, on which the said toothed wheel rotates loosely, a sprocket-chain adapted to engage the said toothed wheel, a spring connected at one end to the said sprocket-chain and at its other end to the car, and means, substantially as described, for drawing the said sprocket-chain in contact with the said toothed wheel, substantially as shown and described.

3. In a car-starter, the combination, with a toothed wheel held loosely on one of the car-axes, of spring-pawl's pivoted on said toothed

wheel, a ratchet-wheel secured on the respective car-axe, on which the said toothed wheel rotates loosely, a sprocket-chain adapted to engage the said toothed wheel, a spring connected at one end to the said sprocket-chain and at its other end to the car, a rope connected with the said sprocket-chain, a clutch-wheel connected with the said rope and mounted to turn loosely on the front axle, and a clutch-tooth held on one of the front axle-wheels and adapted to be engaged by the said clutch-wheel, substantially as shown and described.

4. In a car-starter, the combination, with a toothed wheel held loosely on one of the car-axes, of spring-pawl's pivoted on said toothed wheel, a ratchet-wheel secured on the respective car-axe, on which the said toothed wheel rotates loosely, a sprocket-chain adapted to engage the said toothed wheel, a spring connected at one end to the said sprocket-chain and at its other end to the car, a rope connected with the said sprocket-chain, a clutch-wheel connected with the said rope and mounted to turn loosely on the front axle, a clutch-tooth held on one of the front axle-wheels and adapted to be engaged by the said clutch-wheel, and means, substantially as described, for throwing the said clutch-wheel in and out of gear with the said clutch-tooth, substantially as shown and described.
